[57] CLAIM

The ornamental design for an electronic identification tag for livestock, substantially, as shown and described.

DESCRIPTION

FIG. 1 is a perspective view of an electronic identification tag for livestock according to the present invention;

FIG. 2 is a top plan view of the tag shown in FIG. 1;

FIG. 3 is a front elevational view of the tag shown in FIG. 1;

FIG. 4 is a side elevational view of the tag shown in FIG. 1;

FIG. 5 is a rear elevational view of the tag shown in FIG. 1;

FIG. 6 is a bottom plan view of the tag shown in FIG. 1; FIG. 7 is a perspective view of an alternative embodiment of the electronic identification tag for livestock according to the present invention;

FIG. 8 is a top plan view of the tag shown in FIG. 7;

FIG. 9 is a front elevational view of the tag shown in FIG. 7;

FIG. 10 is a side elevational view of the tag shown in FIG. 7;

FIG. 11 is a rear elevational view of the tag shown in FIG. 7; and,

FIG. 12 is a bottom plan view of the tag shown in FIG. 7.
